UNITED STATES PATENT OFFICE

2,306,453

FIRE TRUCK

John M. Madden, Chicago, Ill., assignor to Leo L. Fitzgerald, Chicago, Ill.

Application April 3, 1941, Serial No. 386,619

7 Claims. (Cl. 228—14)

This invention relates to improvements in fire trucks particularly that type of truck adapted to carry and support an aerial ladder, and refers specifically to a truck of the class described wherein the aerial ladder structure is totally enclosed during non-use of the ladder.

Fire trucks of the type which carry and support aerial ladders have heretofore carried the ladder structure together with the "fly" ladders carried thereby, in an open and exposed position on top of the vehicle. In going to and from fires, in snowy or sleety weather, the ladder structure together with the ladders become covered with snow or ice. A snow covered or ice covered ladder when used at a fire is not only dangerous to the firemen but the snow or ice interferes with the ready manipulation of the aerial ladder and thus decreases the effectiveness of the unit.

My invention contemplates a fire truck which carries and supports an aerial ladder structure, the ladder structure being completely enclosed, the invention being characterized in that access can be gained to the ladder structure and the ladder structure raised in the shortest possible time and with the least possible expenditure of work on the part of the fire fighting crew.

Other objects and advantages of my invention will be apparent from the accompanying drawings and following detailed description.

In the drawings, Fig. 1 is a perspective view of a fire truck of the tractor-trailer type having a completely enclosed aerial ladder.

Fig. 2 is a transverse sectional view taken on line 2—2 of Fig. 1.

Fig. 3 is an end elevational view of a portion of the front end of the trailer, taken on line 3—3 of Fig. 1.

Fig. 4 is a view similar to Fig. 3 showing the split covers in open or operative position.

Fig. 5 is a detailed elevational view, partly in section, illustrating the ladder structure of the aerial ladder in operative position.

Fig. 6 is a plan sectional view, taken on the line 6—6 of Fig. 5.

Fig. 7 is a transverse sectional view of the ladder structure, taken on line 7—7 of Fig. 5, the fly ladders being extended.

Fig. 8 is a fragmentary, perspective view of a fire truck embodying a modification of my invention.

Fig. 9 is a transverse sectional view, taken on the line 9—9 of Fig. 8.

Fig. 10 is a transverse sectional view, taken on the line 10—10 of Fig. 8.

Fig. 11 is a transverse sectional view, taken on the line 11—11 of Fig. 8.

Fig. 12 is a detailed sectional view taken on line 12—12 of Fig. 11.

Referring in detail to the drawings, 1 indicates the tractor portion and 2 the trailer portion of a fire truck. The tractor 1 comprises a cab 3 having doors 4, the cab being adapted to house the driver of the vehicle and other members of the fire company, particularly the officer in charge. The tractor, of course, also carries the engine for driving the truck and for furnishing power in operating certain of the equipment carried by the truck, as will be hereinafter more fully described.

The front end of the trailer 2 is pivotally carried upon platform 5 of the tractor in the usual manner, the rear portion of the tractor being supported upon dirigible wheels 6. A cab 1 is carried at the rear end of the trailer 2 and is adapted to house the tillerman, who steers the dirigible wheels 6, and other members of the fire company. Access to the rear cab is gained through door 8 which opens onto steps 9 and running board 10. The steps 9 are mounted over the rear fender or mud guard 11.

The major portion of the length of the trailer is employed to carry and house the power-operated extensible aerial ladder, hereinafter more fully described.

Referring particularly to Fig. 2, a transverse sectional view of the ladder housing section 12 of the trailer is shown. The housing section 12 is divided vertically into two compartments 13 and 14 by a partition 15. The lower compartment 14 is adapted to house hand ladders, poles, axes and other portable equipment usually carried by the truck. Access is gained to the lower compartment through the rear, the compartment being provided with doors 16.

The upper compartment carries an aerial ladder 17 which is mounted, at the forward end of the trailer upon a turntable 18, which is rotatable by means of shaft 19, which, in turn, may be driven, by suitable transmission means (not shown) by the tractor engine.

The aerial ladder 17 comprises a ladder structure or frame 20, constructed of aluminum or a light-weight high-strength alloy. A pair of spaced supports 21 mounted upon the turntable 18 pivotally connects the frame 20 to the turntable whereby the ladder structure 20 may be swung from inoperative position within the compartment 13 to an operative position, for instance, as shown in full lines in Fig. 5. Lad-

der 22, having rungs 23, comprises a unitary portion of the ladder structure 20, and a plurality of fly-ladders 24, 25 and 26 are extensibly mounted within the structure. The ladder structure 20 is conventional and, except in this particular form of my invention, is mounted in a substantially conventional manner. However, in this form of my invention, the ladders per se are mounted adjacent the top of the ladder structure, when the structure is in inoperative position, whereas the ladders in the usual structure are carried at the bottom of the structure. The reason for this reversal of position will be apparent as the description proceeds.

As a feature of my invention a plate or panel 27 is secured to the ladder structure 20 adjacent the ladder 22, and functions as a closure for the space provided by the side walls of the trailer. When the ladder structure 20 is in inoperative position, the panel 27 completely closes the compartment 13 thereby protecting the ladder structure and ladders from the elements.

Adjacent the front end of the trailer 2, the turntable 18 and forward end of the ladder structure are covered by a hood 28. The hood 28 comprises two sections 29 and 30 respectively hinged at 31 and 32 to the body of the trailer. When the ladder structure is in inoperative position, the hood 28 is closed, as shown in Figs. 1 and 3 in full lines, and in dotted lines in Fig. 4. The forward end of compartment 13 is closed by a stationary panel 33.

A pair of shafts 34 and 35 project from the front end of the trailer 2 and are adapted to be rotated by any suitable connection to the tractor engine, said shafts rotating in opposite angular directions. An arm 36 is rigidly secured to shaft 34 and a similar arm 37 is rigidly secured to shaft 35. Both arms 36 and 37 are of hollow construction and carry, in telescopic relation, arms 38 and 39 respectively. The ends of arms 38 and 39 are respectively, pivotally connected to sections 29 and 30 of hood 28, as shown best at 40 and 41 in Figs. 3 and 4. The hood section 29 comprises panels 42, 43 and 44 which are hinged together at 45 and 46. Similarly, hood section 30 comprises panels 47, 48 and 49, hinged together at 50 and 51.

In operation, to open the hood 28 to expose the forward end of the ladder structure 20 and the turntable 18, shafts 34 and 35 are respectively rotated in counterclockwise and clockwise directions respectively (Figs. 3 and 4). When shafts 34 and 35 are so rotated the respective panels comprising each hood section break about the hinges 45, 46, 50, 51, and 31 and 32. Of course, as the arms 36 and 37 move, the points 40 and 41 assume different distances from shafts 34 and 35. This movement is accommodated by the sliding relationship of arms 36 and 38, and arms 37 and 39. To close the hood, the shafts 34 and 35 rotate in the opposite directions, that is, shaft 34 rotates clockwise and shaft 35 rotates counterclockwise until the hood sections are in the position shown in Fig. 3, the telescopic arms functioning to provide different radii as the hinges close. When the hood is in open position, the hood sections overhang the rear fender of the tractor and provide ready access to, and free movement, of, the ladder structure.

As has been hereinbefore described the ladder structure is pivotally mounted upon supports 21 upon turntable 18. To raise the ladder structure to the vertical position from its inoperative position, a pair of hydraulic lifts are employed.

The hydraulic lifts comprise cylinders 52 and 53, both of which are pivotally mounted upon turntable 18, one on each side of the ladder structure and rearwardly of the supports 21. Piston rods 54 and 55 operate within cylinders 52 and 53 respectively, the ends of said rods being pivotally connected in a pair of transverse slots 56, one of which is shown, provided in the opposite sides of the ladder structure.

In operation, when the ladder structure is in inoperative position within the trailer 2, the cylinders 52 and 53 are in substantially vertical position upon turntable 18, as shown at Fig. 5 in broken lines. In this position the pistons are at the bottoms of the cylinders and the ends of the piston rods are at the upper ends of slots 56. The cylinders 52 and 53 are connected to a suitable source of fluid under pressure, and when it is desired to raise the ladder structure from its inoperative position, fluid under pressure is introduced into the lower portions of said cylinders. The movement of the piston rods, of course, cause the ladder structure to swing about the supports 21 until the vertical position is reached.

A second pair of hydraulic cylinders 57 and 58 are pivotally mounted upon the turntable 18, the piston rods 59 and 60 respectively being pivotally connected to the ladder structure in slots 61, one of which is shown, which are substantially parallel to slots 56. Cylinders 57 and 58 are mounted in advance of the supports 21 and serve to control the ladder structure when it has moved beyond the vertical position, as shown in full lines in Fig. 5. When the ladder structure is in inoperative position the piston rods 60 and cylinders 57 and 58 are in a position as indicated in broken lines in Fig. 5.

The disposition and length of slots 61 with respect to slots 56 is such that when piston rods 54 and 55 have raised the ladder structure to the vertical position, piston rods 60 are at the ends of slots 61 and, hence, by controlling the withdrawal of liquid from cylinders 57 and 58, the ladder structure may be brought to a desired angular position beyond the vertical. When the ladder structure has moved beyond the vertical, the ends of rods 54 and 55 move freely through slots 56, as shown best in Fig. 5.

The aerial ladder 20 is used only in its position beyond the vertical which accounts for the fact that the ladders 22, 24, 25 and 26 are at the top of the structure when the same is in inoperative position. Of course, by the provision of the turntable 18, after moving the ladder structure beyond the vertical it may be swung to any desired position and the fly ladders may be extended as occasion demands.

When the ladder structure is moved to inoperative position, the reverse operation of the hydraulic lifts takes place and the ladder structure together with its attached closure 27 moves into the position shown in Figs. 1 and 2. The hood 28 may then be closed.

It is to be understood, of course, that conventional remote controls are contemplated. For instance shafts 34 and 35, cylinders 52, 53, 57 and 58 and turntable shaft 19 may be controlled from either or both cabs 3 and 7 or controls may be positioned at any other desired portion of the vehicle.

In addition to providing a completely enclosed ladder structure, provision is also made for housing all of the men of the fire company. Further, with the tiller man positioned in the cab 7

rather than on top of the ladder structure, as has heretofore been the case, the ladder structure may be raised more quickly. As a matter of fact it is possible to start raising the aerial ladder before the vehicle comes to a stop. Of course, duplicate manual control of the hood 28 and ladder structure may be provided, in case the tractor engine or connecting transmission becomes inoperative.

Referring in details to Figs. 8 and 12 inclusive, a modification of my invention is shown. The reference numeral 62 indicates the trailer portion of a fire truck which is adapted to be operated with a tractor portion similar to tractor 1. A rear cab 63 is positioned at the rear end of the trailer and is adapted to house the tiller man and members of the fire company.

A major portion of the length of the trailer 62 is devoted to the housing of an aerial ladder 64 which is similar in all essential details to the aerial ladder 17 hereinbefore described. The ladder 64 comprises a ladder structure 65 which carries a fixed ladder 66 which carries a plurality of extensible fly-ladders 67, 68 and 69. The ladder structure 65 is pivotally mounted at its forward end, upon supports 70, which, in turn, are mounted upon a turntable 71.

A pair of hydraulic lifting cylinders 72 are pivotally mounted upon the turntable 71, said cylinders having cooperating pistons and piston rods 73 which are connected to opposite sides of the ladder structure 65 in slots similar to slots 56. The relationship of cylinders 72 to the ladder structure 65 is identical with the relationship of cylinders 52 and 53 to the ladder structure 29, and they function in a similar manner. In this form of my invention, however, only one pair of cylinders is employed, since it is not necessary to move the aerial ladder beyond the vertical position. Hence, the fly-ladders are disposed at the bottom of the ladder structure 65 when the ladder is in inoperative position.

In this form of my invention the body portion of the trailer comprises opposite side walls 74 and 75 and a partition 76 which divides the interior thereof into compartments 77 and 78. The upper portion of the walls 74 and 75 converge and the terminal edges thereof are spaced from each other to provide a passageway for the raising of the ladder 64.

As a feature of my invention a closure 79 spans the space between the edges of the walls 74 and 75. The closure 79 comprises two elongated panels 80 and 81 which are adapted to abut adjacent longitudinal edges when they are in closed position.

A wall 82 is positioned at the front end of the rear cab 63, in which a pair of slots 83 are provided, said slots sloping outwardly and downwardly from the central-top portion of the wall. At the rear end of the panels 80 and 81, outwardly extending pins are provided which carry rollers 84 which project into said slots, said rollers being positioned adjacent the abutting edges of said panels.

A pair of shafts 85 and 86, which are preferably power driven, are journaled in wall 82 and carry pinions 87 and 88 respectively. The pinions 87 and 88 mesh with each other and mesh with pinions 89 and 90 respectively, which latter are carried upon shafts 91 and 92 respectively. Arms 93 and 94 are carried by shafts 91 and 92, respectively, said arms being pivotally connected at their outer ends to panels 80 and 81 respectively, as shown at 95 and 96 in Fig. 10.

In operation, to open the closure 79, shafts 91 and 92 are respectively rotated in clockwise and counterclockwise direction (Fig. 10). In so rotating panels 80 and 81 are moved outwardly, the adjacent longitudinal edges being guided by the grooves or slots 83, until the panels occupy a position as shown in broken lines in Fig. 10. When in this position the aerial ladder may be moved from its inoperative position within the trailer body.

In order to prevent deflection of the panels 80 and 81 along their length when they are in closed position, the outer longitudinal edges carry rollers 97 at spaced points along the length of the trailer body. Curved tracks 98 are carried by the sides 74 and 75 of the trailer body in which said rollers are supported, the tracks terminating adjacent the terminal edges of said side walls. The tracks 98, of course, are spaced along the length of the trailer body in conformity with the position of the rollers 97.

It will be noted that the outer longitudinal edges of the panels 80 and 81 are beveled, as shown at 99 in Figs. 10 and 11, and at the lower portion of each bevel, a lip 100 is formed. The lips 100 carry the rollers 97, and when said panels are in closed position the outer edges of the panels are suspended from the tracks 98 thereby preventing said panels from deflecting. When the panels are opened the outer edges of the panels are guided by the tracks 98 in a downwardly curved direction, the arrangement being such that the panels can be moved to open position without interference from the ladder structure.

To provide support for the abutting edges of the panels, spacing blocks 101 are carried, at spaced points along the length of the panels, which rest upon the ladder structure when the panels are in closed position.

The front end of the trailer 62 is similar in construction to that of trailer 2, hereinbefore described, that is, a hood is provided for covering the turntable 71, similar to hood 28.

It is to be understood, of course, that I do not wish to be limited to the specific mechanism herein described for raising or lowering the aerial ladder or for moving the panels and hood, since my invention is broadly directed to a completely closed fire truck with means for moving an aerial ladder therefrom.

I claim as my invention:

1. A fire truck for carrying an aerial ladder which comprises, a vehicle body having a compartment therein, a horizontal turntable positioned in said compartment, an aerial ladder positioned in said compartment and pivotally connected at one end to said turntable for movement in a vertical plane, said compartment adjacent said turntable being defined by a removable hood, means for moving said hood to expose said turntable and the portion of the ladder secured thereto, the remaining portion of said body being provided with an elongated opening above said ladder, a removable closure for said opening, and means for moving said ladder in a vertical plane through said opening about its pivotal support when said closure has been removed.

2. A fire truck for carrying an aerial ladder which comprises, a vehicle body having a compartment therein, an aerial ladder positioned in said compartment and pivotally supported on said body adjacent an end thereof for swingable movement in a vertical plane, said body having an elongated opening above said ladder, a closure for said opening carried by said ladder for closing

said opening when the ladder is in said compartment, and means for lifting said ladder and closure from said compartment in a vertical plane about said pivotal support.

3. A fire truck for carrying an aerial ladder which comprises, a vehicle body having a compartment therein, an aerial ladder positioned in said compartment and pivotally supported on said body adjacent an end thereof for swingable movement in a vertical plane, said body having an elongated opening above said ladder, a closure for said opening carried by said ladder for closing said opening when the ladder is in said compartment, and hydraulic means for lifting said ladder and closure from said compartment in a vertical plane about said pivotal support. 5

4. A fire truck for carrying an aerial ladder which comprises, a vehicle body having a compartment therein, an aerial ladder positioned in said compartment and pivotally supported on said body adjacent an end thereof for swingable movement in a vertical plane, said body having an elongated opening above said ladder, a closure for said opening carried by said ladder for closing said opening when the ladder is in said compartment, and means for lifting said ladder and closure from said compartment in a vertical plane about said pivotal support and positioning said ladder at an angle greater than ninety degrees from its position within said compartment. 20

5. A fire truck for carrying an aerial ladder which comprises, a vehicle body having a compartment therein, a turntable horizontally positioned in said compartment, an aerial ladder positioned in said compartment and pivotally supported at one end on said turntable for swing- 35

able movement in a horizontal and vertical plane, said body having an elongated opening above said ladder, a closure for said opening carried by said ladder for closing said opening when the ladder is in said compartment, and means for lifting said ladder and closure from said compartment in a vertical plane about said pivotal support.

6. A fire truck for carrying an aerial ladder which comprises, a vehicle body having a compartment therein, an aerial ladder longitudinally positioned in said compartment and pivotally supported adjacent one end in said compartment, said body having an elongated opening at its top, a removable closure for said opening, said closure comprising two elongated panels, means for moving said panels transversely to a position within said body to expose said ladder, and means for lifting said ladder through said opening about its pivotal support when said panels have been moved to open position. 15

7. A fire truck for carrying an aerial ladder which comprises, a vehicle body having a compartment therein, an aerial ladder longitudinally positioned in said compartment and pivotally supported adjacent one end in said compartment, said body having an elongated opening at its top, a removable closure for said opening, said closure comprising two elongated panels, means for moving said panels transversely to a position within said body to expose said ladder, means for guiding said panels during movement thereof, and means for lifting said ladder through said opening about its pivotal support when said panels have been moved to open position. 25

JOHN M. MADDEN.
